Primary Examiner — Elizabeth J Oswecki(57) **CLAIM**

The ornamental design for a delivery box, as shown and described.

DESCRIPTION

FIG. 1 is a perspective view of a delivery box showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a cross-sectional view taken along the line 9-9 shown in FIG. 3; and,

FIG. 10 is an enlarged portion view taken from encircled portion labeled, "FIG. 10," in FIG. 1.

The dash-dash broken lines in the drawings depict portions of the delivery box that form no part of the claimed design. The dot-dash broken lines represent the boundary of the enlarged portion view of FIG. 10 shown in FIGS. 1 and 10 that form no part of the claimed design.
